US00D845746S

(12) **United States Design Patent** (10) **Patent No.:** **US D845,746 S**
(45) **Date of Patent:** **** Apr. 16, 2019**

(54) **BASKET HOLDER**

(71) Applicant: **CLAIRSON, INC.**, Newark, DE (US)

(72) Inventors: **Milind Sahebrao Nimgulkar**, Pune (IN); **Gajanan Ramkishan Muttepawar**, Pune (IN); **Harishchandra Namdeo Dahatonde**, Pune (IN)

(73) Assignee: **Clairson, Inc.**, Newark, DE (US)

(**) Term: **15 Years**

(21) Appl. No.: **29/615,639**

(22) Filed: **Aug. 30, 2017**

Related U.S. Application Data

(60) Division of application No. 29/576,481, filed on Sep. 2, 2016, now Pat. No. Des. 807,735, which is a continuation of application No. 15/131,323, filed on Apr. 18, 2016, now Pat. No. 9,596,931.

(57) **CLAIM**

The ornamental design for a basket holder, as shown and described.

DESCRIPTION

FIG. 1 is a perspective view of a first embodiment of a basket holder showing our new design;

FIG. 2 is a front view of the basket holder shown in FIG. 1;

FIG. 3 is a back view of the basket holder shown in FIG. 1;

FIG. 4 is a right side view of the basket holder shown in FIG. 1;

FIG. 5 is a left side view of the basket holder shown in FIG. 1;

FIG. 6 is a top view of the basket holder shown in FIG. 1; and,

FIG. 7 is a bottom view of the basket holder shown in FIG. 1.

1 Claim, 3 Drawing Sheets
